United States Patent Office

Des. 186,595
Patented Nov. 10, 1959

186,595

AIR PURIFIER FAN CASING OR SIMILAR ARTICLE

Wallace A. Monson, St. Paul, Minn., assignor to Brown
& Bigelow, St. Paul, Minn.

Application November 3, 1958, Serial No. 53,258

Term of patent 14 years

(Cl. D26—7)

FIG. 1

FIG. 2

FIG. 3

FIG. 4

FIG. 5

Fig. 1 is a perspective view of an air purifier fan casing or similar article showing my new design;

Fig. 2 is a top plan view thereof;

Fig. 3 is a side elevational view thereof;

Fig. 4 is a diametrical cross-sectional view; and

Fig. 5 is a bottom plan view.

I claim:

The ornamental design for an air purifier fan casing or similar article, as shown.
